DUPLICATING MACHINE

Wilhelm F. Schoenhardt, Chicago, Ill., assignor to
 Ditto, Incorporated, Chicago, Ill., a corporation
 of West Virginia

Application May 19, 1939, Serial No. 274,583

17 Claims. (Cl. 271—53)

This invention relates to duplicating apparatus of the type in which the reading matter or other design to be duplicated is carried in reverse on a master copy such as the usual gelatin band 5 mounted about a drum. Copy sheets are fed to the drum and pressed by an impression roller or platen into operative engagement with the band as the drum rotates for printing such copy sheets.

It is the object of the present invention to provide an improved form and arrangement of the parts in apparatus of the type described whereby improved results may be obtained.

The invention is directed particularly to the 15 mechanism whereby, as the drum rotates, the sheets are fed one at a time to the drum and brought into the proper adjusted position with respect to the design on the gelatin band for providing the desired margins on the printed sheet.

The apparatus embodies mechanism whereby sheets are fed from a stack directly into position to be engaged by the gelatin band as the drum rotates. The apparatus embodies also means by which the sheets are stripped from the gelatin band and control means for the feed and stripping mechanisms whereby, at the will of the operator, a sheet may be applied to the gelatin band and caused to pass a plurality of times between the drum and the platen roller, and the platen roller may be moved into and out of 30 operative position with respect to the drum.

It is another object of this invention to provide improved apparatus of the character described whereby to simplify the operation of feeding and 35 positioning sheets with respect to a duplicating drum and a platen roller.

The features and advantages of the present invention will appear more fully as the description proceeds, reference being had to the accompanying drawings wherein a preferred form of the 40 invention is shown.

In the drawings,

Fig. 1 is a view in side elevation of the improved apparatus with the end frame thereof 45 broken away;

Fig. 2 is an enlarged fragmentary sectional view taken on the line 2—2 of Fig. 1;

Fig. 3 is a top plan view of the apparatus shown in Fig. 1, with certain of the parts partially broken away so as to be shown in horizontal section;

Fig. 4 is an end view partly in section, taken substantially on the line 4—4 of Fig. 1;

Fig. 5 is an enlarged view in side elevation, 50 similar to Fig. 1, showing only a portion of the

mechanism at the right-hand end of Fig. 1 and showing the parts in a changed position;

Fig. 6 is a fragmentary view similar to Fig. 5, illustrating a further changed position of the parts;

Fig. 7 is a fragmentary sectional view taken on the line 7—7 of Fig. 6;

Fig. 8 is a fragmentary sectional view taken on the line 8—8 of Fig. 6;

Fig. 9 is a fragmentary sectional view taken on the line 9—9 of Fig. 6;

Fig. 10 is a fragmentary sectional view taken on the line 10—10 of Fig. 3;

Fig. 11 is a fragmentary sectional view similar to Fig. 10, showing the parts in a changed position, and

Fig. 12 is a further fragmentary view similar to Fig. 10, but showing another position of the parts.

Referring now to the several figures of the drawings, in which corresponding parts are indicated by the same reference characters, 30 indicates a frame which in the arrangement shown comprises standards 31 and 32 oppositely arranged (see Figs. 3 and 4) supporting a drum 33 25 by means of two short aligned shafts 34 and 35. The drum 33 is segmental in form as is usual in connection with gelatin-process duplicating machines, being provided with suitable mounting means of any approved type, as is indicated diagrammatically in Fig. 1, for mounting a gelatin band 36 about the face portion of the drum, the drum at the leading and rear edges of the face portion being provided with rollers 37 for engaging the gelatin band (see Figs. 1, 10 and 11). 35 The arrangement is such that the gelatin band 36 can be shifted as desired circumferentially of the segmental face portion of the drum.

Means is provided for driving the drum 33, as is best shown in Figs. 1 and 3, comprising a drive 40 pulley 38 connected by means of a belt 39 with any suitable source of power, said pulley 38 being rotatably mounted upon the standard 31 of the frame by means of a short stub shaft 40. The pulley 38 is provided at one side face with a pinion 41 rigidly connected therewith in position to mesh with a large gear 42 rotatably mounted upon the short shaft 34 by means of a collar 43. The gear 42 in turn is provided on its outer face portion with a ratchet wheel 44 which is adapted 50 to be engaged by a pawl 45 pivotally mounted upon the adjacent face of a large gear 46 fixedly mounted upon the shaft 34 so as to rotate with the drum 33. No means is shown in the drawings for controlling the position of the pawl 45 by 55

which power may be transmitted from the gear 42 to the gear 46. Control means of any approved type is to be employed as is well understood in the art for regulating the position of the pawl 45 in accordance with the requirements. Such control means are not shown since they form no part of the present invention.

Upon the opposite end of the drum from that at which the gear 46 is mounted thereon, I have provided three cams 47, 48 and 49, rigidly mounted upon the drum so as to rotate therewith for purposes as hereinafter described.

At the rear end of the machine (see Figs. 1 and 4) I have provided extending frame bars 52 connected with parts 50 and 51 of the framework 30 for supporting a table 53 thereon, together with means for feeding the topmost sheet from a pile of copy sheets resting on the table. At opposite sides of the table, operating mechanism is provided in connection with the feed of the sheets from the table. As is clearly shown in Fig. 4, the table 53 is preferably provided with adjustable side margin bars 54 and 55 at opposite sides of the table for holding the sheets in evenly piled relation to each other. In the arrangement shown, the margin bars 54 and 55 are held in frictional engagement with the table 53 by means of coiled springs 56, the arrangement being such that the margin bars are readily movable inwardly and outwardly with respect to each other to correspond with the width of the sheets being used.

The means for feeding to the drum the topmost sheet from a pile of sheets supported by the table 53 comprises means intermittently driven in timed relation to the rotation of the drum 33. This means comprises a bell-crank lever 57 pivotally mounted upon the standard 32 by means of a stub shaft 58. The bell-crank lever has a roller 59 rotatably mounted upon one of its arms in position to be engaged by the cam 49 at a predetermined point in each rotation of the drum 33. The other arm of the bell-crank lever 57 is connected by means of a link 60 with the lower end of an arm 61 which is pivotally mounted upon the adjacent frame member 52 at one side of the table 53. The arrangement is such that as the drum 33 rotates in clockwise direction to the position as shown in Fig. 1, the roller 59 and the bell-crank lever 57 are displaced in counter-clockwise direction in said Fig. 1 for swinging the arm 61 also in counter-clockwise direction in said figure. A coiled spring 62 connected between a pin 61a on the movably mounted arm 61 and a collar 58a on the shaft 58 serves to swing the movably mounted arm 61 in clockwise direction as soon as the cam 49 has cleared the roller 59 for permitting such result. An eccentric stop device 63 is adjustably mounted upon the frame member 52 in position to engage the edge of the arm 61 for limiting the movement of said arm in clockwise direction in said Fig. 1.

At opposite sides of the table 53, I have provided standards 64 rising from the frame members 52 respectively for supporting a drive shaft in position across the table in upwardly spaced relation thereto. In the arrangement shown (Figs. 1, 2 and 3), the drive shaft is built up from a plurality of parts, comprising a short shaft section 66 which is journaled in a bearing 65 carried by the upper end of one of the standards 64, and a long sleeve member 68 removably mounted at one end on said shaft section 66 so as to rotate therewith. At its inner end, the sleeve member 68 is slidably mounted upon a shaft

section 69 which in turn is rotatably mounted in the side wall of a housing 70 as hereinafter described, the sleeve member 68 and the shaft section 69 being connected so as to rotate together. By this arrangement, the shaft 69 is caused normally to rotate with the shaft section 66, but the two shafts are adapted very quickly and easily to be disconnected from each other by a sliding movement of the tubular member 68 toward the housing.

The means for driving the shaft comprising the sections 66 and 69 includes a pinion 76 operatively mounted on the shaft section 66 by clutch members 73, 74 and 75 so as to drive said shaft section in one direction, said pinion 76 being in mesh with gear teeth 77 on the upper end of the pivotally mounted arm 61. The arrangement is such that upon a stroke of the arm 61 in counter-clockwise direction in Fig. 1 the shaft is driven in clockwise direction.

The means for supporting the housing 70 in position comprises a sleeve 71 rigidly connected at its inner end with one side wall of the housing 70 in axial alignment with the shaft section 69. At its opposite end, the sleeve 71 has a releasable connection 72 with the upper end portion of the adjacent standard 64. The arrangement of the shaft comprising the sections 66 and 69 and the connections of said shaft as above described with the housing 70 and sleeve 71 are such as to hold the parts strongly in operative position during the operation of the machine. When the operator desires, however, the shaft and connected parts can be very quickly and easily removed from position. For accomplishing this purpose, the sleeve 68 is first moved toward the housing 70 for disengagement from the shaft section 66, and the whole assembly is then moved toward the near side in Fig. 3 for freeing the sleeve 71 from the frame.

Within the housing 70, in the arrangement shown, I have provided driving connections between the shaft section 69 and a short shaft 78 which extends through the side walls of the housing 70 and has rollers 79 and 80 fixedly mounted upon its outer end portions. The arrangement is such that when the shaft sections 66 and 69 are driven in clockwise direction in Fig. 1 by reason of an operative stroke of the arm 61 in counter-clockwise direction, the rollers 79 and 80 are likewise driven in clockwise direction in said Fig. 1 for moving the topmost sheet of a pile of sheets 81 (see Figs. 6 and 10) toward the left. Upon the return movement of the arm 61 by the spring 62, the free-wheeling connection as above described permits the rotation of the pinion 76 with respect to the shaft section 66 so as not to change the position of the rollers 79 and 80.

In the arrangement as above described, the housing 70 serves as an arm for spacing the rollers 79 and 80 from the shaft section 69, such arm extending across above the table in spaced relation to the table, the rollers 79 and 80 being held by their own weight in operative engagement with the pile of sheets 81. In case the operator should desire to move the rollers 79 and 80 out of engagement with the pile of sheets, this can be accomplished by merely swinging the housing 70 and its connected parts about the shaft section 69 and the sleeve 71 so as to carry the rollers 79 and 80 upwardly and backwardly past the axis of the shaft section 66.

In Fig. 1 the roller 59 is shown in engagement with the cam 49 at the forward end of the operative stroke of the rollers 79 and 80 for forward-

ing a sheet of the pile 81 toward the left in said figure. In Fig. 5, in which the parts are shown in the changed position which they assume upon a further advance movement of the drum from the position as shown in Fig. 1, the bell-crank lever 57 has been partially returned by the spring 62 to starting position. The rollers 79 and 80, when rotated in clockwise direction in Fig. 1, move the top sheet of the pile of sheets 81 into the position shown in Fig. 10. The sheet, in its advance movement, is guided between a downwardly curved guide plate 82 on the table 53 and an upper guide plate 83. The guide plate 83 is mounted upon two raised portions 84 and 85 of the side frames 52. The upper edge of the guide plate 83 is turned up vertically, as shown as 86, so as not to interfere with the positioning of the pile of sheets 81. The plate 82 on the table and the guide plate 83 provide a tapering throat which is adapted to direct a copy sheet over the surface of a platen roller 87 into a margin bar 87a. The plate 82 ends directly over the platen roller 87 and is tangent to that part of the roller which is engaged by the advancing gelatin band 36. The margin bar 87a is in line with the plate 82.

The platen roller 87 is mounted upon two pivoted arms 88 and 89 (see Figs. 4, 5 and 6). The arms 88 and 89 are pivoted to the frames 52 by two pivot pins 90 and 91. The platen roller 87 has a shaft 92 which is journaled in the arms 88 and 89. At the opposite ends of the arms 88 and 89 from the shaft 92 pins 93 and 94 extend inwardly through two slots 95 and 96 provided in the frames 52. These pins are connected to links 97 and 98 which are, in turn, connected to two arms 99 and 100 fixed on a control shaft 101. The shaft 101 is journaled in suitable bearings 102 and 103 in the frames 52. Two collars 104 and 105 are fixed on the shaft 101 which is inside the bearings 102 and 103, and the arms 99 and 100 are mounted on these collars. The shaft 101 projects through the left-hand frame 52, as shown in Fig. 4, and has a sleeve 106 fixed thereon. A control lever 107 is secured to the sleeve 106 and has a handle 108 thereon by which the shaft 101 may be rocked to swing the platen roller 87 to and from the drum 33. A spring 99a is connected between the arm 99 and a pin 99b on the frame 52 so as to yieldingly urge the platen roller 87 toward the drum 33.

The shaft 101 has a sleeve 109 rotatably mounted thereon at the end of the sleeve 106. This sleeve 109 carries a stripper control lever 110 which is provided with a handle 111. The stripper control lever 110 is connected to a link 112 which leads to the stripper mechanism which will be presently described. A collar 113 is fixed on the end of the shaft 101 to hold the sleeve 109 in place.

The margin bar 87a is carried by two arms 114 and 115. The arms 114 and 115 are fixed to a margin bar shaft 116 which is journaled in the frames 52. This shaft extends through the frames 52 and at one end is provided with an arm 117 which connects to a spring 118 that is under tension between the arm and a pin 119 fixed on the right-hand frame member 52, as shown in Fig. 4. At the other end of the margin bar shaft 116 there is provided an arm 120 which carries a roller 121 adapted to engage the cam 48 (see Figs. 3, 5-7). As illustrated best in Figs. 5 and 6, the cam 48 has a rounded nose portion 122 which strikes the roller 121 at the instant

the advancing gelatin band 36 reaches the platen roller 87 as shown in Fig. 11 and immediately swings said roller 121 in a counter-clockwise direction about the shaft 116, as viewed in these figures. The margin bar 87a is thus moved away from the forward edge of the copy sheet held thereby to allow the copy sheet to follow the gelatin band and be pressed against the band on the drum by the platen roller 87. The arm 117, which urges the margin bar into the position shown in Figs. 5 and 10, has a flange 123 thereon which is adapted to engage an eccentrically mounted stop 124 on the frame 52. The stop 124 is adjustable so as to vary the position of the margin bar with respect to the platen roller 87 and control the length of margin left at the advancing end of the copy sheet. The arm 120 can be adjusted on the shaft 116 by means of a slot 120a in the arm 120 and a screw 120b threaded into a collar 116a on the shaft 116 (see Fig. 7) for controlling the position of the cam roller 121 with respect to the margin bar 87a.

Referring now to the stripper mechanism which is shown most clearly in Figs. 1 and 3, the construction comprises a main stripping roller 125 mounted on a shaft 126 which is journaled in the side frames 31 and 32. This shaft carries a pinion 127 that meshes with the gear 46 for rotating the roller 125 in counterclockwise direction in Fig. 1. A guide roller 128 cooperates with the roller 125 to direct the advancing edge of a copy sheet outwardly from the drum upon a receiving tray 129. The roller 128 is carried by two arms 130 and 131. These arms are supported by a shaft 132 which is journaled in two studs 133 and 134 mounted on the side frames 31 and 32. The shaft 132 carries two stop members 135 and 136 which are adapted to engage a cross tie rod 137 so as to limit the movement of the arms 130 and 131 and the roller 128 toward the drum. A spring 138 (see Fig. 1) is connected to one end of a lever 13 which is fixed to the shaft 132. The other end of this spring is connected to a pin 140 on the side frame 32. The purpose of the spring 138 is to urge the shaft 132 and the arms 130 and 131 to turn in a clockwise direction so as to bring the roller 128 toward the drum surface. The lever 139 carries a cam roller 141 which rides on the cam 47.

The cam 47 is so shaped as to direct the roller 128 into the path of the advancing edge of a copy sheet and then to move the roller outwardly so as to clear the advancing edge of the gelatin band. This movement of the roller 128 outwardly serves to bring the copy sheet into engagement with the rotating roller 125 and to press the sheet against the roller for stripping the sheet from the drum. It is desirable in many instances to maintain a sheet on the gelatin band for more than one rotation of the drum. The link 112 is provided with means whereby the stripping mechanism which was just described may be rendered inoperative to strip a sheet from the drum. It will be noted that the link 112, as shown in Fig. 1, has an elongated slot 142 which receives a guide pin 143 on the side frame 32. The link 112 is bent outwardly at 144 (see Fig. 3) so as to follow the frame 32 from the front end of the machine to the rear thereof. A bar 145 is mounted on the link 112 and extends into overlapping relationship with the spring connected end of the lever 139. Referring now to Figs. 1 and 3, if it is desired to render the stripping means inoperative, the lever 110 is pushed in a counter-clockwise direction so as to move the link 112 to the right from the

position shown in Fig. 1. This will bring the screw 146 into engagement with the lever 139 and prevent the spring 138 from swinging this lever in a clockwise direction about the shaft 132.

5 When the roller 141 rides off of the cam 47, the stripping roller 128 will still be held in the position shown in Fig. 1 and will be inoperative to engage the advancing edge of a copy sheet on the drum. Thus the sheet may be left on the drum for as

10 many rotations thereof as are desired.

The means for holding the platen roller 87 out of contact with the drum have been previously described in detail. The operation of this means is briefly as follows: Assuming that it is desired 15 to prevent the platen roller from engaging the drum, for any purpose such as an inspection of the design on the gelatin band, the operator may move the platen roller control lever 107 in a clockwise direction from the position shown in 20 Figs. 1 and 3. This will swing the shaft 101 in a clockwise direction, causing the arms 99 and 100 and links 97 and 98 to turn the arms 88 and 89 in clockwise direction and move the platen 25 roller outwardly from the drum. It is desirable to limit the movement of the platen roller toward the drum, and for this purpose an eccentrically mounted stop 147 is provided on the frame 52 in position to engage the end of the arm 88, as is shown in Fig. 6.

30 The operation of the sheet feeding mechanism and the margin bar is best illustrated in Figs. 10, 11 and 12. In Fig. 10, the parts are in a position where the copy sheet has been fed into the 35 margin bar 87a and the drum 33 is advancing to engage its gelatin band 36 with the copy sheet. It is obvious that more or less margin may be left between the point of engagement of the sheet with the platen roller and the engagement of the sheet with the margin bar. This adjustment can be 40 made by means of the eccentric stop 124. The shortness of the margin is limited only by the necessary clearance between the platen roller and the margin bar. In Fig. 11, the parts are shown at the instant when the gelatin band 36 engages 45 the copy sheet. It is at this point that the forward end 122 of the cam 48 engages the roller 121 to move the margin bar out of the way. Since the cam 48 projects beyond the periphery of the 50 drum, it will move the margin bar shaft enough to quickly separate the margin bar from the advancing edge of the copy sheet. In Fig. 12, the margin bar is shown in its completely retracted position corresponding to the cam position for the cam 48 55 illustrated in Fig. 6. The margin bar is held in this position until the roller 121 approaches the rear end of the cam 48 where the cam slopes inwardly to allow the roller 121 to gradually return the margin bar to its operative position illustrated in Fig. 10.

60 While I have shown and described a preferred embodiment of my invention, it is to be understood that it is capable of many modifications. Changes, therefore, in the construction and arrangement may be made without departing from the spirit and scope of the invention as described in the appended claims, in which it is my intention to claim all novelty inherent in my invention as broadly as possible, in view of the prior 65 art.

Having thus described my invention, what I claim as new and desire to secure by Letters Patent is:

I claim:

75 1. A duplicating machine of the character de-

scribed comprising a frame, a drum journaled therein providing an arcuate platen, a duplicating band on said platen, a platen roller movably mounted in said frame in the path of said band and adapted to press sheets against the band, a 5 margin bar, arms carrying said bar and pivoted in the frame to swing the bar into and out of operative position in the path of the platen beyond the platen roller, a copy sheet table on said frame, a sheet guide on said table extending 10 toward the drum and terminating directly over the platen roller in close proximity to the path of the platen in position to guide sheets across said roller to the margin bar and to contact the sheets with that part of the roller which lies in 15 the path of the advancing band on the drum, sheet feeding means for advancing sheets from said table to the margin bar, and actuating means for said margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the 25 platen.

2. A duplicating machine of the character described comprising a frame, a drum journaled therein providing an arcuate platen, a duplicating band on said platen, a platen roller movably mounted in said frame in the path of said band and adapted to press sheets against the band, a margin bar, arms carrying said bar and pivoted in the frame to swing the bar into and out of operative position in the path of the 35 platen beyond the platen roller, a copy sheet table on said frame, a sheet guide on said table extending toward the drum and terminating directly over the platen roller in close proximity to the path of the platen in position to guide sheets 40 across said roller to the margin bar and to contact the sheets with that part of the roller which lies in the path of the advancing band on the drum, said sheet guide comprising upper and lower plates directed diagonally downward and 45 converging toward the drum, sheet feeding means for advancing sheets from said table to the margin bar, and actuating means for said margin bar operable in timed relation with the drum to place the bar in position to receive a sheet 50 riding over said guide and said platen roller until the sheet has engaged the margin bar and has been pressed by the platen roller against the duplicating band and to thereafter remove the bar from the path of the platen. 55

3. A duplicating machine of the character described comprising a frame, a drum journaled therein providing an arcuate platen, a duplicating band on said platen, a platen roller movably mounted in said frame in the path of said band 60 and adapted to press sheets against the band, a margin bar, arms carrying said bar and pivoted in the frame to swing the bar into and out of operative position in the path of the platen beyond the platen roller, a copy sheet table on 65 said frame, a sheet guide on said table extending toward the drum and terminating directly over the platen roller in close proximity to the path of the platen in position to guide sheets across said roller to the margin bar and to contact the sheets with that part of the roller which lies in the path of the advancing band on the drum, sheet feeding means for advancing sheets from said table to the margin bar, and actuating means for said margin bar operable in 70 75

- timed relation with the drum to place the bar in position to receive a sheet riding over said guide and said platen roller until the sheet has engaged the margin bar and has been pressed by the platen roller against the duplicating band and to thereafter remove the bar from the path of the platen, said actuating means comprising a cam fixed to the drum at one end thereof and a roller at one end of the margin bar to engage said cam.
4. A duplicating machine of the character described comprising a frame, a drum journalled therein providing an arcuate platen, a duplicating band on said platen, a platen roller movably mounted in said frame in the path of said band and adapted to press sheets against the band, manually controlled means for moving the platen roller out of the path of the band, a margin bar, arms carrying said bar and pivoted in the frame to swing the bar into and out of operative position in the path of the platen beyond the platen roller, a copy sheet table on said frame, a sheet guide on said table extending toward the drum and terminating directly over the platen roller in close proximity to the path of the platen in position to guide sheets across said roller to the margin bar and to contact the sheets with that part of the roller which lies in the path of the advancing band on the drum, sheet feeding means for advancing sheets from said table to the margin bar, and actuating means for said margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen.
5. A duplicating machine of the character described comprising a frame, a drum journalled therein providing an arcuate platen, a duplicating band on said platen, a platen roller movably mounted in said frame in the path of said band and adapted to press sheets against the band, manually controlled means for moving the platen roller out of the path of the band, a margin bar, arms carrying said bar and pivoted in the frame to swing the bar into and out of operative position in the path of the platen beyond the platen roller, a copy sheet table on said frame, a sheet guide on said table extending toward the drum and terminating directly over the platen roller in close proximity to the path of the platen in position to guide sheets across said roller to the margin bar and to contact the sheets with that part of the roller which lies in the path of the advancing band on the drum, sheet feeding means for advancing sheets from said table to the margin bar, and actuating means for said margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen.
6. A duplicating machine of the character described comprising a frame, a drum journalled therein providing an arcuate platen, a duplicating band on said platen, a platen roller movably mounted in said frame in the path of said band and adapted to press sheets against the band, a margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen, said actuating means comprising a cam fixed to the drum at one end thereof and a roller at one end of the margin bar to engage said cam.
7. A duplicating machine of the character described comprising a frame, a drum journalled therein providing an arcuate platen, a duplicating band on said platen, a platen roller movably mounted in said frame in the path of said band and adapted to press sheets against the band, a margin bar, arms carrying said bar and pivoted in the frame to swing the bar into and out of operative position in the path of the platen beyond the platen roller, a copy sheet table on said frame, a sheet guide on said table extending toward the drum and terminating directly over the platen roller in close proximity to the path of the platen in position to guide sheets across said roller to the margin bar and to contact the sheets with that part of the roller which lies in the path of the advancing band on the drum, sheet feeding means for advancing sheets from said table to the margin bar, and actuating means for said margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen.
8. A duplicating machine of the character described comprising a frame, a drum journalled therein providing an arcuate platen, a duplicating band on said platen, a platen roller movably mounted in said frame in the path of said band and adapted to press sheets against the band, a margin bar, arms carrying said bar and pivoted in the frame to swing the bar into and out of operative position in the path of the platen beyond the platen roller, means to adjust the operative position of said bar toward and away from said platen roller, a copy sheet table on said frame, a sheet guide on said table extending toward the drum and terminating directly over the platen roller in close proximity to the path of the platen in position to guide sheets across said roller to the margin bar and to contact the sheets with that part of the roller which lies in the path of the advancing band on the drum, sheet feeding means for advancing sheets from said table to the margin bar, and actuating means for said margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen.

- platen roller in close proximity to the path of the platen in position to guide sheets across said roller to the margin bar and to contact the sheets with that part of the roller which lies in the path 5 of the advancing band on the drum, sheet feeding means for advancing sheets from said table to the margin bar, and actuating means for said margin bar operable in timed relation with the drum to place the bar in position to receive a 10 sheet riding over said guide and said platen roller until the sheet has engaged the margin bar and has been pressed by the platen roller against the duplicating band and to thereafter remove the bar from the path of the platen, said sheet 15 guide comprising a plate curved downwardly from the table and terminating in a portion which is substantially tangential to the platen roller at the point where the advancing band first presses the sheets against the platen roller, 20 and a top plate above said curved plate, said plates converging toward the platen roller to provide a tapered passage for directing copy 25 sheets tangentially across the platen roller to the margin bar.
14. A duplicating machine of the character described comprising a frame, a drum journaled therein providing an arcuate platen, a duplicating band on said platen, a platen roller movably mounted in said frame in the path of said band 30 and adapted to press sheets against the band, a margin bar, arms carrying said bar and pivoted in the frame to swing the bar into and out of operative position in the path of the platen beyond the platen roller, means to adjust the operative 35 position of said bar toward and away from said platen roller, a copy sheet table on said frame, a sheet guide on said table extending toward the drum and terminating directly over the platen roller in close proximity to the path of the platen 40 40 in position to guide sheets across said roller to the margin bar and to contact the sheets with that part of the roller which lies in the path of the advancing band on the drum, sheet feeding means for advancing sheets from said table to the margin bar, and actuating means for said 45 margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen, said sheet guide comprising a plate curved downwardly from the table and terminating in a portion which is substantially tangential to the platen roller at the point where the advancing band first presses the sheets against the platen roller.
15. A duplicating machine of the character described comprising a frame, a drum journaled therein providing an arcuate platen, a duplicating band on said platen, a platen roller movably mounted in said frame in the path of said band and adapted to press sheets against the band, manually controlled means for moving the platen 65 roller out of the path of the band, a margin bar, arms carrying said bar and pivoted in the frame to swing the bar into and out of operative position in the path of the platen beyond the platen roller, means to adjust the operative position 70 of said bar toward and away from said platen roller, a copy sheet table on said frame, a sheet guide on said table extending toward the drum and terminating directly over the platen roller in close proximity to the path of the platen in position to guide sheets across said roller to the
- margin bar and to contact the sheets with that part of the roller which lies in the path of the advancing band on the drum, sheet feeding means for advancing sheets from said table to the margin bar, and actuating means for said margin bar operable in timed relation with the drum to place the bar in position to receive a sheet riding over said guide and said platen roller until the sheet has engaged the margin bar and has been pressed by the platen roller against the duplicating band and to thereafter remove the bar from the path of the platen, said sheet guide comprising a plate curved downwardly from the table and terminating in a portion which is substantially tangential to the platen roller at the point where the advancing band first presses the sheets against the platen roller, and a top plate above said curved plate, said plates converging toward the platen roller to provide a tapered passage for directing copy 20 sheets tangentially across the platen roller to the margin bar.
16. In a duplicating machine of the character described, the combination of a frame, a drum rotatably mounted on said frame and cut away at one side to provide an arcuate platen, means for rotating said drum, means for holding a duplicating band wrapped about said platen, a platen roller rotatably mounted on said frame and standing normally in the path of said platen 30 and movable outwardly a short distance into pressure relationship with said platen for pressing a sheet against the duplicating band on the platen as the drum rotates, guiding means for directing a sheet fed thereto into position across the face of said platen roller, a margin bar movable toward and from the drum adapted when disposed inwardly to engage the leading edge of a sheet fed into position opposite to the face of said platen roller for accurately positioning the sheet for engagement with said duplicating band, and controlling means for said margin bar adapted to hold the margin bar disposed inwardly in operative stopping position until said platen is brought into pressure relationship with said platen roller and adapted thereafter to move the margin bar quickly out of the path of the platen.
17. In a duplicating machine of the character described, the combination of a frame, a drum rotatably mounted on said frame and cut away at one side to provide an arcuate platen, means for rotating said drum, means for holding a duplicating band wrapped about said platen, a platen roller rotatably mounted on said frame and movable toward and from the bottom face of the drum at the downwardly moving side of the drum, yielding means adapted normally to press the platen roller inwardly into position for operative engagement with said platen as the drum rotates, a margin bar movable toward and from the drum adjacent to said platen roller, means for holding said margin bar normally in position adjacent to the face of said platen roller, guiding means for directing a sheet fed thereto into position across the face of said platen roller and into engagement with said margin bar so as to be positioned thereby, and means actuated in timed relation to the rotation of the drum adapted to withdraw said margin bar quickly from the path of said platen after the forward edge of the platen has pressed the duplicating band into holding engagement with the sheet by cooperation with said platen roller.
